OR THE LIKE**

Julian R. Haynes, Hinsdale, Ill., assignor to Sunbeam
Corporation, Chicago, Ill.

Filed July 12, 1971, Ser. No. 161,372

Term of patent 14 years

Int. Cl. D15—05

U.S. Cl. D49—17

FIG. 1 is a perspective view of a tool holder for vacuum cleaner or the like embodying my new design;

FIG. 2 is a side elevational view thereof showing the side opposite that shown in FIG. 1;

FIG. 3 is a top plan view thereof;

FIG. 4 is an end elevational view thereof; and

FIG. 5 is a longitudinal sectional view taken along the section line 5—5 of FIG. 3.

The vacuum cleaner shown in broken lines in FIG. 1 is for the purpose of illustrating environmental structure which forms no part of the claimed design.

I claim:

The ornamental design for a tool holder for vacuum cleaner or the like, as shown and described.
